Inventor:
Justus R. Kinney,
by Walter E. Lombard.
Atty.

UNITED STATES PATENT OFFICE.

JUSTUS R. KINNEY, OF JAMAICA PLAIN, MASSACHUSETTS.

LIFTING JACK.

Application filed February 28, 1924. Serial No. 695,860.

To all whom it may concern:

Be it known that I, JUSTUS R. KINNEY, a citizen of the United States of America, and a resident of Jamaica Plain, in the county 5 of Suffolk, in the State of Massachusetts, have invented certain new and useful Improvements in Lifting Jacks, of which the following is a specification.

This invention relates to lifting jacks and 10 particularly to devices of this character adapted for use in connection with motor vehicles.

The object of the invention is the production of a lifting jack which is provided with 15 an out-board support adapted to be lowered sufficiently to permit its insertion beneath the axle of a motor vehicle provided with balloon tires, when a tire is deflated.

The invention consists primarily of a vertical rack, having a carriage adapted to be moved lengthwise of said rack, said carriage having mounted thereon a pinion coacting with the teeth of said rack and driving mechanism for said pinion.

The invention further consists of certain 25 novel features of construction and arrangement of parts which will be understood readily by reference to the description of the drawings and to the claims to be hereinafter given.

For the purpose of illustrating the invention, one preferred form thereof is illustrated in the drawings, this form having been found to give satisfactory and reliable 35 results although it is to be understood that the various instrumentalities of which the invention consists can be variously arranged and organized and the invention is not limited to the precise arrangement and organization 40 of these instrumentalities as herein shown and described except as required by the scope of the appended claims.

Of the drawings:

Figure 1 represents a plan of a lifting 45 jack embodying the principles of the present invention.

Figure 2 represents a side elevation of the same, and

Figure 3 represents a front elevation of 50 the same.

Similar characters indicate like parts throughout the several figures of the drawings.

In the drawings 10 is a base plate having 55 secured thereto the end plate 11 and side plates 12.

The side plates 12 have a pivot pin 13 mounted therein extending through the lower end of a rack 14 which may be of any desired length. 60

The rack 14 is provided with teeth 15 on one face and with these teeth 15 mesh the teeth of a pinion 16 formed upon a revoluble shaft 17 rotatable in bearings in the side walls of a carriage 18 adapted to be moved 65 endwise of said rack 14.

The carriage 18 consists of a U-shaped plate having mounted in its open end a pin 19 on which is a roller 20 the periphery of which bears against the rear face 21 of the 70 rack 14 and prevents the carriage 18 from tilting when a weight is disposed upon its outwardly extending support 22.

The upper end of the outwardly extending support 22 is concaved as indicated at 75 23 and when an axle A is positioned thereon said axle will bear against the vertical wall 24 of the said carriage 18. This concaved end 23 of support 22 prevents the accidental displacement of the axle A when once positioned upon said support. 80

The worm gear 25 is fixedly secured to one end of the shaft 17 and this worm gear meshes with a worm 26 fixedly secured to an actuating shaft 27 mounted in bearings 85 in ears 28 extending outwardly from one side wall of the carriage 18.

Pivotedly secured to one end of the actuating shaft 27 is a rod 29 by means of which the shaft 27 may be rotated in any well 90 known manner.

The shaft 17 has secured thereto a collar 30 which with the gear 25 at its opposite end prevents end movement of said shaft.

The carriage 18 is also provided with another roller 31 which travels over the ends of the teeth 15 and assists in preventing the tilting of the carriage 18 when supporting a load. 95

By making a pivotal connection between 100 the base 10 and the lower end of the rack 14 the base may rest upon uneven ground and the rack maintained in a vertical position.

It will be noted that the support 22 is at one side of the vertical rack 14 and when 105 a load is positioned thereon the tendency would be to tilt the carriage 18 thereby causing it to bind upon the rack and prevent free movement of the carriage 18 on the rack 14.

The rollers 20, 31 effectually prevent this binding of the carriage 18 upon said rack 110.

14 and permit the carriage to move freely.

The roller 20 may be used alone if desired, but preferably the roller 31 is also used.

5 The support 22 may be lowered to a point near the base 10 and then inserted beneath the axle A of a vehicle the tire of which is deflated and if the worm 27 is then rotated, rotary movement will be imparted to 10 the shaft 17 through the worm gear 25 thereby causing the carriage 18 to be raised or lowered as desired.

When the load upon the support 22 is in raised position it will be retained in this 15 position by the engagement of the teeth of the worm gear 25 with the thread of the worm 26.

The pitch of the thread of worm 26 is such as to prevent the rotation of the worm 20 by the tendency of the worm gear 25 to rotate when a load is on the support 22.

Each side wall of the carriage 18 has a flanged collar 32 mounted therein with the inner ends thereof contacting with the side 25 walls of the rack 14 thereby preventing any lateral movement of the carriage 18 as it travels up and down the rack 14.

The device is constructed at a minimum cost but is very effective when in operation.

It is believed that the operation and many advantages of the invention will be apparent without further description.

Having thus described my invention, I 35 claim—

1. The combination of a base; a rack secured at its lower end to said base; a carriage movable endwise on said rack and having an outwardly extending support; a

shaft mounted in bearings in the side walls 40 of said carriage; a pinion thereon coacting with said rack; means mounted on said carriage for rotating said shaft; and collars on said shaft at opposite ends of said pinion having peripheral flanges coacting with the 45 sides of said rack.

2. The combination of a base; a rack secured at its lower end to said base and provided with an unbroken back face extending from side to side thereof; a carriage movable endwise on said rack and having an outwardly extending support; a shaft mounted in bearings in the side walls of said carriage; a pinion thereon coacting with said rack; means mounted on said carriage for rotating said shaft; and a roller at the upper end of said carriage coacting with the back face of said rack.

3. The combination of a base; a rack secured at its lower end to said base; a carriage movable endwise on said rack and having an outwardly extending support; a shaft mounted in bearings in the side walls of said carriage; a pinion thereon coacting with said rack; means mounted on said carriage for rotating said shaft; and two rollers on said carriage at different levels, the lower roller coacting with the front face of said rack; and the upper one coacting with the back face of said rack.

Signed by me at 746 Old South Building, Boston, Massachusetts, this 27th day of February, 1924.

JUSTUS R. KINNEY.
